UNITED STATES PATENT OFFICE.

WILLIAM K. MANN, OF ARKANSAS CITY, KANSAS.

SPINNING TOP AND SUPPORT THEREFOR.

1,411,974.

Specification of Letters Patent.

Patented Apr. 4, 1922.

Application filed February 27, 1920. Serial No. 361,730.

To all whom it may concern:

Be it known that I, WILLIAM K. MANN, a citizen of the United States, and a resident of Arkansas City, in the county of Cowley 5 and State of Kansas, have invented a new and Improved Spinning Top and Support Therefor, of which the following is a full, clear, and exact description.

The invention relates to games and toys, 10 and its object is to provide a new and improved spinning top and support therefor arranged to hold a spinning top suspended without interfering with the revolving of the spinning member. Another object is 15 to afford considerable amusement to the user of the toy and to onlookers.

With these and other objects in view, the invention consists of certain novel features of construction as hereinafter shown and 20 described and then specifically pointed out in the claims.

A practical embodiment of the invention is represented in the accompanying drawings forming a part of this specification, in 25 which similar characters of reference indicate corresponding parts in both views.

Figure 1 is a perspective view of the spinning top and the support therefor; and

Figure 2 is a similar view of a modified 30 form of the same.

The improved toy illustrated in Figure 1 consists essentially of a magnet 10, one or two spinning tops 11 alike in construction, and a suspension means 12, in the form of a 35 string, for holding the magnet 10 in suspended position by the operator of the toy, as indicated in Figure 1. The magnet 10 is shown as of the permanent horseshoe type but I do not limit myself to this particular form of magnet as the same may 40 be in the form of a bar or an electromagnet. Each of the spinning tops 11, shown in Figure 1, comprises a spindle 15 on which is secured a disk-shaped body 16, and the spindle 15 terminates in pointed ends 17 and 18 and the spindle is provided adjacent the pointed end 18 with an armature 19, preferably in the form of soft iron in the shape of a knob or a bead. It will be noticed 45 that by the arrangement described the top 11 can be spun by the user of the toy in the usual manner with the point 17 in spinning engagement with a table top or

other surface, and then one of the legs of the magnet 10 is moved adjacent the other 55 pointed end 18 whereby the armature 19 is attracted to permit of lifting the spinning top 11 off the table or other surface with the pointed end 18 in spinning engagement with the face of the corresponding leg of 60 the magnet 10. It will further be noticed that two tops 11 while spinning may be supported on the two legs of the magnet 10 in the manner above described, and as the magnet 10 is held suspended by the 65 user of the toy the latter is rendered exceedingly attractive both to the user and the onlookers.

As shown in Figure 2, the magnet 10 and its suspension means 12 are the same as 70 shown in Figure 1, but the toy 20 is in the form of a gyroscopic toy having a frame 21, a spindle 22 journaled in the frame and carrying a body 23. The frame 21 is provided with stems 24, 25 in alinement with 75 the spindle 22, and the said stems 24 and 25 terminate in armatures 26, 27, preferably in the form of soft iron knobs, either of which is adapted to be attracted by one leg of the magnet 10 while the other leg of 80 the magnet engages the frame 21 to hold the gyroscopic toy suspended on the magnet 10, and while the body 23 and its spindle 22 rotate in the frame 21.

Having thus described my invention, I 85 claim as new and desire to secure by Letters Patent:—

1. In a toy, the combination of a spinning top having a body and a spindle, provided with pointed ends, the spindle on one side of 90 the body being longer than on the other, an armature fixed on the spindle adjacent the pointed end of the longer spindle portion, and a permanent horse shoe magnet having either leg adapted to attract the said armature to hold the adjacent points in spinning contact with the base of the corresponding magnet leg.

2. In a toy, the combination of a spinning top having a body and a spindle provided 100 with pointed ends, an armature fixed on the spindle adjacent one of the said pointed ends, a permanent horseshoe magnet having either leg adapted to attract the said armature to hold the adjacent point in spinning 105 contact with the face of the corresponding

magnet leg, and suspension means connected with the bend of the said magnet to hold the latter suspended.

3. In a toy spinning top, a spindle having 5 pointed ends, a relatively large disk-shaped body on the spindle near one end and arranged at right angles to the axis thereof, and a relatively small soft iron arma-

ture similarly positioned on the spindle near the other end and in the form of 10 a knob or bead, one or more of said tops being adapted to be attracted and suspended from the legs of a horse shoe or other magnet at the armature end.

WILLIAM K. MANN.
